UNITED STATES PATENT OFFICE.

JOSEPH ATWOOD WHITE, OF PHILADELPHIA, PENNSYLVANIA, ASSIGNOR TO THE MOORE AND WHITE COMPANY, OF PHILADELPHIA, PENNSYLVANIA, A CORPORATION OF PENNSYLVANIA.

PAPER-SLITTING MACHINE.

1,026,482.

Specification of Letters Patent.

Patented May 14, 1912.

Application filed September 5, 1911. Serial No. 647,570.

To all whom it may concern:

Be it known that I, JOSEPH A. WHITE, a citizen of the United States, residing in Philadelphia, Pennsylvania, have invented 5 certain Improvements in Paper-Slitting Machines, of which the following is a specification.

The object of this invention is to provide mechanism for slitting paper as it is being 10 wrapped in the form of a roll. This object I attain in the following manner, reference being had to the accompanying drawings, in which:

Figure 1, is a longitudinal sectional view 15 of a machine for wrapping paper in the form of a roll illustrating my improved cutting mechanism for cutting the roll of paper into strips; Fig. 2, is an enlarged sectional view of part of the mechanism illustrated 20 in Fig. 1, taken on the line 2—2, Fig. 3; Fig. 3, is a face view looking in the direction of the arrow 3, Fig. 2; Fig. 4, is a sectional plan view on the line 4—4, Fig. 2; Fig. 5, is a detached perspective view of one 25 of the bearings; Fig. 6, is an enlarged sectional view of part of Fig. 4; Figs. 7 and 8, are views of a modification, and Fig. 9, is a side view illustrating another modification.

A is the frame, B B' are the two drums 30 which support and wind the roll of paper C upon a mandrel c, the ends of the mandrel being adapted to guides a in the frame.

D is a conveying belt which passes under the roller B and around the belt wheels d d', 35 the wheel d, in the present instance, being the driven wheel. The belt D is made of a series of bands spaced a given distance apart, and located between the bands are deflectors e carried upon a bracket e' which 40 direct the paper into the space between rolls B B', so that it can be wrapped around the mandrel c. The paper may come direct from a paper making machine or may come from another drum upon which the paper 45 has been previously wound.

It is desirable in many instances to cut the paper into strips and this has usually been accomplished by a slitting machine placed in advance of the rolls, and the paper 50 has been slit into longitudinal lengths prior to being rolled on the mandrel c. In the present instance I utilize the roll of paper as the platen for the cutting knives, and place the cutting mechanism, which is illus-

trated at I, above the roll of paper, as indicated in Fig. 1, and I mount the cutters on a transverse tubular bar I'. Secured to the bar is a series of brackets N made in halves and clamped by screws n n', as clearly illustrated in Fig. 2. A feather n² is clamped 55 between the halves of the bracket and extends into a slot in the bar I' so that while the brackets can be shifted longitudinally on the bar they are held from turning thereon by the feather. 60

As illustrated in Fig. 2, the bracket N has a segmental slot k adapted to receive the bolt i upon which the bearings M M are pivoted. These bearings are connected together at their outer ends by a bolt m on 70 which is pivoted a set bolt h having nuts located on each side of a projection of the bracket N. Projecting from each bearing M is a hub m', Figs. 4 and 5, on which the presser rollers s s are mounted. In each hub is a hole m² located off center, the two holes are in line, and extending through the holes is a spindle f' on which is mounted the cutter f which is very thin so as to make a narrow cut in the paper. Surrounding 75 the spindle f' are sleeves f² which bear upon the sides of the blade and are held against the blade by the head of the spindle at one end and the nut at the opposite end, as shown in Figs. 4 and 6. 80

By locating the pivot of the cutter blade off center and at the rear of the presser rollers, the rollers hold the paper in advance of the cutter, thus making a clean cut, and the cutter blade can be made very thin as 90 it is held laterally by the rollers s s close to the cutting point, yet it can penetrate the paper to the desired depth owing to its being located off center in respect to the rolls. By making a very narrow cut in the paper 95 the wall on each side of the cut will properly support the sheet being cut, thus making a cut that is not ragged. 85

By mounting the brackets M in the manner illustrated in Figs. 2, 3 and 4, the rotary cutter blade f can be adjusted to enter the roll of paper more or less without disturbing the location of the presser rollers s, as by loosening the bolt i it can slide in the segmental slot K in the bracket and as the 100 curve of this slot is taken from the center of the rollers the bearings M can turn on the rollers as pivots when the nuts of the 105

adjusting bolt are manipulated to adjust the blade f , after which the nuts are tightened and the bolt i clamped firmly in position.

5 It may be necessary to adjust the cutter blades as they wear, or to adjust one or more of the cutting devices according to the character of the paper, as in some rolls there occur soft spots and the cutting devices must be so set that the blades will project into the roll to a greater extent at these points than when the roll is hard. When it is desired to adjust both the rollers s and the cutting blade f , then the bolt i is loosened and the bearings can be bodily adjusted toward or from the roll of paper.

In Figs. 7 and 8, I have shown the bearings M' mounted on a fixed pivot pin i' . In this construction both the rollers and the blade are adjusted together.

In Fig. 9 I have shown the presser rollers s mounted on a bearing M^2 pivoted at i^2 to the bracket N' and having an adjusting bolt h' , and pivotally mounted on the bearing M^2 is a supplementary bearing M^3 carrying the blade f^3 , and h^2 is an adjusting bolt pivotally connected to the bearing M^3 and adjustable in a projection of the bearing M^2 so that each frame can be adjusted independently.

I claim:

1. The combination in a paper slitting machine, of means for winding paper into roll form; a rotary cutter located so as to bear upon and cut the paper of the roll; a presser roller on each side of the rotary cutter; the said rotary cutter being located off center with respect to the presser rollers so that the paper is held on the roll by the presser rollers immediately in advance of the cutting point whereby buckling is prevented due to the action of the cutting blade in severing the paper.

2. The combination in a paper cutting machine, of means for forming a roll of paper; a bracket located in close proximity to the roll; a bearing adjustably mounted on the bracket and carrying a presser roller; and a cutting blade, the cutting blade being arranged off center in respect to the roller; the bearing being adjustable on the center of the presser roller as a pivot so that the blade can be adjusted toward and from the roll of paper independently of the roller.

55 3. The combination of means for forming a roll of paper; a bracket; a bearing; a roller mounted on the bearing; and a rotary cutter

mounted also on the bearing off center in respect to the roller; a segmental slot in the bearing; a bolt extending through the slot and holding the bearing in the position to which it is adjusted; with means for adjusting the bearing.

4. The combination in a paper cutting machine of a frame; two supporting drums for the roll of paper; means for feeding the paper to form the roll; a transverse bar; brackets clamped to the bar; each bracket having a pair of presser rollers; and an intervening rotating cutting blade; the cutting blade being arranged off center in respect to the rollers so that the rollers will hold the paper in advance of the point where the cut is made.

5. The combination of means for forming a roll of paper; a bar; a bracket adjustably mounted on the bar; two bearings pivotally mounted on the bracket; each bearing having a hub; a presser roller mounted on each hub; a rotary cutter located between the hubs; and a spindle on which the cutter is mounted.

6. The combination of means for forming a roll of paper; a bar; a bracket adjustably mounted on the bar; two bearings pivotally mounted on the bracket; each bearing having a hub; a presser roller mounted on each hub; a rotary cutter located between the hubs; a spindle on which the cutter is mounted; sleeves surrounding the spindle and located on each side of the blade and held against the blade by the head of the spindle on one side and a nut on the spindle on the opposite side.

7. The combination of means for forming a roll of paper; a bar; a bracket secured to said bar; two bearings pivotally mounted on the bracket, adjusting means common to both bearings; each bearing having an inwardly extending hub; a presser roller mounted on each hub; a spindle extending through both hubs at one side of the center; a thin circular blade located on the spindle between the hubs; and a sleeve on each side of the blade and through which the spindle extends; said sleeve being held in place by a head and nut on the spindle.

In testimony whereof, I have signed my name to this specification, in the presence of two subscribing witnesses.

JOSEPH ATWOOD WHITE.
